(57) **CLAIM**

I claim the ornamental design for an adjustable kettlebell, as shown and described.

DESCRIPTION

FIG. 1 depicts an exploded front perspective view of a new and ornamental design for an adjustable kettle.

FIG. 2 depicts an exploded front view of FIG. 1.

FIG. 3 depicts an exploded back view of FIG. 1.

FIG. 4 depicts an exploded left side view of FIG. 1.

FIG. 5 depicts an exploded right-side view of FIG. 1.

FIG. 6 depicts an exploded top view of FIG. 1.

FIG. 7 depicts an exploded bottom view of FIG. 1.

FIG. 8 depicts a front perspective view of FIG. 1 with one sleeve attached.

FIG. 9 depicts a left side view of FIG. 8 with one sleeve attached.

FIG. 10 depicts a front perspective view of FIG. 8 with one unattached sleeve.

FIG. 11 depicts a left side view of FIG. 8 with one unattached sleeve.

FIG. 12 depicts a front perspective view of FIG. 8.

FIG. 13 depicts an exploded front perspective view of an alternative embodiment of a new and ornamental design for an adjustable kettle.

FIG. 14 depicts an exploded front view of FIG. 13.

FIG. 15 depicts an exploded back view of FIG. 13.

FIG. 16 depicts an exploded left side view of FIG. 13.

FIG. 17 depicts an exploded right-side view of FIG. 13.

FIG. 18 depicts an exploded top view of FIG. 13.

FIG. 19 depicts an exploded bottom view of FIG. 13.

FIG. 20 depicts a front perspective view of FIG. 13 with two sleeves attached.

FIG. 21 depicts a left side view of FIG. 13 with two sleeves attached.

FIG. 22 depicts a front perspective view of FIG. 13 with two unattached sleeves.

FIG. 23 depicts a left side view of FIG. 13 with unattached sleeves; and,

FIG. 24 depicts a front perspective view of FIG. 13.
